UNITED STATES PATENT OFFICE.

NIELS LARSEN, OF WEST POINT, NEBRASKA.

SUN-DIAL.

SPECIFICATION forming part of Letters Patent No. 281,527, dated July 17, 1883.

Application filed March 17, 1883. (No model.)

To all whom it may concern:

Be it known that I, NIELS LARSEN, of West Point, in the county of Cuming and State of Nebraska, have invented a new and Improved 5 Sun-Dial or Solar Compass, of which the following is a full, clear, and exact description.

My invention consists of a semicircular portion of a ring corresponding to that portion of the globe upon which the shadow of a ball located at the earth's center would travel, supposing the earth to be transparent, arranged in connection with a ball and an adjusting device, and having longitudinal lines of declination and transverse lines for hour-marks, making a simple and efficient sun-dial or solar compass, all as hereinafter fully described.

Reference is to be had to the accompanying drawings, forming part of this specification, in which similar letters of reference indicate corresponding parts in all the figures.

Figure 1 is a perspective view of my improved sun-dial. Fig. 2 is a diagram illustrative of the principle of the invention. Fig. 3 is a perspective view of a dial constructed according to my invention with a modified arrangement for adjusting it for latitude and a modified arrangement for supporting the ball. Fig. 4 is a perspective view of a dial constructed according to my invention with an arrangement for setting off the equation of time so that the dial will show mean solar time.

The principle of the invention is as follows: Supposing the earth to be a transparent globe, with a ball placed in the center, then the shadow of the ball would travel around the globe once in twenty-four hours; and if the sun's declination was south, say, 10° , the shadow of the ball would travel 10° north of the equator. If we then take that portion of a globe lying $23^{\circ}28'$ on each side of the equator, the extent of the sun's declination, with a ball in the center and the upper half cut away, it would form a semicircular ring, on which, if suspended 45 parallel to the equator, the shadow of the ball would travel as on the earth. If we make the ring flat, it will be the tangent of a globe of the ring's diameter, as shown in Fig. 2, and if tangent lines of declination are drawn on this 50 semicircular ring, with a ball suspended in the center, the shadow of the ball will travel along the line of declination all day if the ring is

suspended parallel to the equator—that is, with an angle from the vertical equal to the latitude of the place.

In the drawings, *a* represents such a semicircular ring as above described, which may be suspended on pivots *b*, supported by any suitable uprights, *c*, with an adjustable arc, *d*, for setting it for latitude; or it may be suspended by chains *e* with an adjusting-screw, *f*, for use instead of the arc *d*.

g represents the ball to be set in the center of the ring for casting the shadow, said ball to be supported by a thread, *h*, regulated by screws *n*, or any other approved means. For example, in a simple and cheap device to be carried in the pocket, a frame, *i*, may be used, said frame being mounted on a bottom, *j*, to be attached to the ring. The said frame may be so constructed as to be lowered down and raised up, as may be required.

k represents the line along which the shadow of the ball will pass when the sun is on the equator; *l*, the latitude or declination lines, and *m* the hour-lines.

As shown in Fig. 4, a modified arrangement may be made by which the equation of time may be set off on the instrument so that it will show mean solar time. The semicircular ring *a* is fastened to a bottom, *j*, which forms a half-circle and moves around a screw, *p*, which passes through its center and into the center of another bottom, *r*, also, a half-circle, and a little larger than bottom *j*. The chains *e* are fastened to bottom *r*, and at the back a standard, *s*, is fastened to bottom *r*, to which standard the chain that carries the adjusting-screw *f* is fastened, by which arrangement bottom *r* can be suspended parallel to the plane of the equator, and bottom *j*, with semicircular ring *a*, move freely, also parallel to the plane of the equator, over bottom *r*, around the center *p*, and have a vernier, *t*, connecting the two bottoms, and upon which the equation of time can be set off.

To find the latitude of the place, level the dial about fifteen minutes before the sun comes on the meridian and bring the shadow of the ball on the line of declination for noon of that day. As long as the shadow of the ball goes down the sun is rising, and the shadow must be kept on the line of declination by motion of the latitude-arc *d*, where the hour-line of 12 crosses

the declination-line. When the shadow is at a standstill on the declination-line, it is noon, and the latitude may be read off on the latitude-arc d , and the dial is regulated for that 5 latitude.

If the shadow of the ball is kept on the declination-line it will show the time when it crosses the hour-line.

The standards c , to which the ring a is suspended, can be used as sight-vanes, and will 10 give a true east-and-west line.

The declination-lines, and also the hour-lines, which may be subdivided in proportion to the size of the instrument, may be in several 15 different colors, so as to readily catch the eye.

The instrument may be made of any suitable material.

Cards with the sun's declination and equation of time should go with each instrument, 20 and abridged tables of the same may be printed or fastened on any convenient part of the instrument. The bottom j is also used to keep the semicircular ring in shape.

I do not limit myself to the particular construction herein described, as it is obvious that 25

many different instruments, all carrying out the same general idea, could be made.

I am aware that it is not new to combine a rocking semi-circle, a revolving solar plate pivoted in a top plate and having a small hole 30 for the passage of the sunlight, and two levels at right angles to each other; but

What I do claim as new and of my invention, is—

1. The semicircular ring a , marked with 35 lines $k l m$, arranged on pivots b , and provided with an adjustable arc, d , in combination with the frame i , mounted on a bottom, j , attached to the ring, said frame being adapted to be moved up and down, as shown and described. 40

2. The combination, with the ring a , of the semicircular bottom j , movable about a screw, p , a larger semi-circle, r , parallel to the equatorial line k , and the vernier t , connecting said semi-circles, as shown and described.

NIELS LARSEN.
